REGISTER

William G. Orth, Dayton, Ohio, assignor, by
mesne assignments, to Central National Bank
of Cleveland, Cleveland, Ohio

Application January 14, 1936, Serial No. 59,108

23 Claims. (Cl. 101—66)

Heretofore means have been known whereby the printing mechanism of a register may be operated or not operated at the will of the operator by manipulating an "on and off" lever such as shown, for instance, in the application of Albert S. Wheelbarger and William G. Orth, Serial No. 752,677, filed November 12, 1934. It has also heretofore been proposed to provide means whereby when the clerks' and transaction keys or lever are in certain predetermined positions the machine will issue a ticket but if either the clerks' or the transaction lever or keys move from the said certain position the ticket mechanism will automatically be rendered inoperative and the certifying mechanism will automatically be rendered operative, such as shown in the application of Albert S. Wheelbarger and William G. Orth, Serial No. 34,120, filed August 1, 1935. I now propose to provide a shutter which will normally close the entrance to the certifying mechanism and means whereby when the shutter closes the entrance the ticket printing mechanism will be operated but when the shutter is raised so that a card could be inserted into the certifying mechanism the ticket printing mechanism would be rendered inoperative and the certifying mechanism would be rendered operative.

The object of the invention is to automatically control the operating means for the ticket printing mechanism and the certifying mechanism and this control is fool-proof so that it is impossible to issue a ticket when a card is to be certified and the ticket issuing mechanism is automatically rendered operative when there is no card to be certified.

Referring to the drawings:

Fig. 1 is a side elevational view of the register having my invention incorporated therein;

Fig. 2 is a side elevational view, partly in cross section, of the opposite end of the register from that shown in Fig. 1 and looking in the opposite direction;

Fig. 3 is an elevational view, partly in cross section, of the shutter control mechanism;

Fig. 4 is a side elevational view of the driving disk for the certifying printing mechanism; and

Fig. 5 is an end elevational view of the structure shown in Fig. 2 with the associated parts.

As shown in Patent 1,977,016, the printing carrier 44 is oscillated each time the machine is operated so as to bring the platens carried thereby into contact with the type wheels 53, it being understood, of course, that the ticket strip paper passes over the platen 1 and a strip of record paper passes over the platen 2, each of which platens are carried by the printing carrier 44. As shown in the said patent, the ticket strip 9, after receiving the printed impression, passes beneath a feed roller 8 which is secured to a

pinion 6 and above a feed roller 10 so that when the pinion 6 is rotated anti-clockwise as viewed in Fig. 1 the ticket strip will be fed out of the machine after it has received the printed impression. Record paper 3 passes over the record platen 2 and a printed impression is made thereon each time the platen 2 is oscillated into contact with the type wheels 53.

I have provided a fixed table 4 extending from the front to the back of the register and extending outside of the register so that a certifying card could be placed thereon there being, of course, a slot in the casing of the register through which the certifying card could be inserted. Normally closing this slot is a shutter 5 provided with an upstanding arm 7 which is provided with a slot 11 through which extends a guide pin 12 carried by the register. Slots 13 are also provided in the arm 7 and through these slots extend studs 14 carried by a rod 15 which is provided with a guide slot 16 through which extend fixed studs 17. The arm 7 is also provided with a pin 18 on which is suspended a spring 19 which has its other end attached to the uppermost one of the studs 14. An operator's handle 20 is integral with the arm 7 and extends to the outside of the machine so as to be readily accessible by the operator. A spring 21 is attached to a stud 22, which spring has its opposite end connected with a fixed stud 23 so that this spring tends to depress the rod 15 and through the spring 19 to depress the shutter 5. The upper end of the rod 15 is provided with a slot 24 which receives a pin 25 carried by an arm 26 of a rod 21. Also secured to this rod is a lever 28 which has its lower end lying between studs 23 and 30 carried by a slide bar 31. The slide bar 31 is provided with slots 32 and 33. A stud 34 extends through the slot 33 and this stud is carried by a lever 35 rotatably mounted on a shaft 36. The lever 35 is provided with an arm 37 which has an overturned lug 38 which may be received within a slot 39 in a disk 40 secured to the feed roller 8. The lever 35 is also provided with an arm 41 which carries a shaft 42 on which is mounted a pinion 43, which pinion when operated by the mechanism shown in said Patent 1,977,016 would, of course, feed out the ticket strip 9 after it has received the printed impression from the platen 1. A conventional aligning pawl 46 is provided for the pinion 43.

A stud 47 projects through the slot 32 in the slide bar 31, which stud is carried by a plate 48 pivoted on a shaft 49. The plate 48 has an overturned flange 50 which overlies the slide bar 31. An arm 51 pivoted on a shaft 52 normally abuts against the flange 50 and prevents the plate 48 being rotated in an anti-clockwise direction but the arm 51 is provided with a cam surface 54 so that when the slide bar 31 is moved to the left 60

as viewed in Fig. 1 the said slide bar will engage the cam surface 54 and elevate the arm 51 against the tension of the spring 38. A link 53 extends between the studs 34 and 47 so that the 5 said studs always occupy the same relative positions in their respective slots; that is, if the stud 47 is at the left-hand end of its slot, the stud 34 will be at the left-hand end of its slot, and vice versa. The plate 48 is provided with notches 57 and 58 which are engaged by a retaining pawl 55 which is urged into contact with the notches by means of a spring 60.

The plate 48 carries a stud 61 on which is suspended a link 62 connected to a stud 63 carried by an arm 64 secured to a shaft 65. Suspended from the stud 63 is a link 66 connected by means of a stud 67 to a lever 68 pivoted on a shaft 69. The lever 68 is provided with a plate 70 which when the plate is in the position shown in Fig. 20 1 will be engaged by an arm 71 of a lever 72, which lever 72 will raise the shaft 73 on which the platen 1 is mounted when the machine is operated as shown in said Patent 1,977,016 so that the platen will bring the ticket paper into engagement with the type wheels 68 but if the plate 70 were depressed so that it could not be engaged by the arm 71 the shaft 73 would remain in the lower end of the slot 75 in the oscillating printing carrier 64 and, therefore, the platen would not engage the type wheels when the machine was operated.

Secured to the shaft 65 at the opposite end of the machine from the arm 64 is a lever 73 provided with a stud 76 on which is mounted a roller 77 received within a curved slot 78 in the lever 73, which lever is mounted on a shaft 79. Movable with the lever 73 is a lever 81 provided with a stud 82 carried by a shifting plate 83. As shown in the application 752,277 above-mentioned this shifting plate is provided with a square lug 84 adapted to be received within a cut-away portion 85 of a plate 86 mounted on a shaft 87. The shifting plate 83 is provided with a circular cut-away portion 86 which receives a disk 88 provided with a slot 89 and a radially extending lug 90, said lug having a part which projects laterally beyond the face of the disk. Within the slot 89 is a bifurcation 91 which is a part of the plate 86. As the shifting plate 83 is moved upwardly and to the right as viewed in Fig. 2 it carries the disk 88 with it so as to engage the radially extending lug 90 carried by the disk 88 with the bifurcation 91 of plate 86 and with lugs 94 on a disk 95 which is rigidly secured to the shaft 87. In the position of the parts shown in Fig. 2 wherein the handle 23 is down so that the shutter closes the opening to the certifying mechanism, the main operating shaft 27 may be rotated without imparting any movement to the plate 86 for the radially extending lug 90 does not connect the disk 88 secured to the shaft 87 with the bifurcation 91 forming a part of the plate 86, but if the shifting plate 83 were raised, as would be the case 65 when the handle 23 were elevated, the lug 90 would be removed from the cut-away portion 85 in the plate 86 so that the plate 86 would be free to rotate and the lug 90 would extend between the lugs 94 carried by the disk 88 and the bifurcation 91 in the plate 86 so that the plate 86 would rotate with the drive shaft.

The plate 86 is provided with a box cam 96 which receives a roller 97 carried by a lever 98 mounted on a shaft 99, which lever 98 has a downwardly extending arm 100 which operates a

platen 100 pivoted on a shaft 101 so as to engage the certifying strip on the table 4 with the type wheels 102. Obviously the platen would be operated as many times as there are lobes on the box cam 95.

Also secured to the shutter 5 is a link 103 connected to a lever 104, which lever is mounted on a shaft 105. This lever is provided with a stud 106 which normally is received within a notch 107 in the plate 86. This mechanism serves as an additional safe-guard to prevent the plate 86 being rotated when it should not be rotated and yet provides mechanism to free the plate 86 when it should be operated.

A motor bar 108 should be pressed inwardly 15 when the machine is to be operated electrically and this bar is provided with a cam surface 109 terminating in a surface 110 extending in the same length-wise direction as the motor bar 108. Resting on this motor bar is a roller 111 carried by a stud 112 mounted on a lever 113 pivoted on a shaft 114. This lever 113 is provided with a stud 115 on which is mounted a roller 116 adapted to contact either the cam surface 110 or the cam surface 118 of a depending arm 119 25 carried by the slide bar 31.

In operation, if no certifying card is inserted in the machine, that is, if the handle 23 is not raised, the machine will print on the detail strip 3 and on the ticket strip 3 and will issue a ticket. 30 For such an operation the parts are in the position shown in the drawings in which it will be noted that the plate 70 is in a position to engage the arm 71 and elevate the platen 1 and also the pinion 43 is in engagement with the pinion 35 6 so that the ticket will be both printed and issued. When the motor bar 108 is pushed inwardly the roller 116 will engage the cam surface 117 of the slide bar 31 so as to insure that the left-hand end of the slot 33 will engage the 40 pin 34 and hold the pinion 43 in engagement with the pinion 6.

When, however, it is desired to certify the operator pulls upwardly on the handle 23 and inserts the certifying strip into the machine on 45 the table 4. The certifying slip limits the depression of the shutter 5. When the operator pulls upwardly on the handle 23 he elevates the arm 7 and the spring 18 pulls upwardly on the upper stud 14, thereby elevating the rod 15. If 50 any obstruction were encountered, that is, if the parts were a little stiff so that the tension of the spring were insufficient to overcome the inertia, the lower portion of the slots 13 would engage the studs 14 and positively raise the rod 15 which 55 would rotate the arm 23 and lever 28 clockwise as viewed in Fig. 3 and anti-clockwise as viewed in Fig. 2 so that the lever 28 would engage the stud 29 and shift the slide bar 31 to the left as viewed in Figs. 1 and 3, so that the cam surface 60 118 would be above the roller 116. If now the motor bar 108 is depressed the roller 116 would engage the cam surface 118 and shift the slide bar 31 as far as possible to the left as viewed in said figures, so that the slide bar would engage the 65 cam surface 54 and raise the arm 51 out of engagement with the flange 59 and the plate 43 would be shifted counter-clockwise so as to disengage the pawl 59 from the notch 58 and to engage it in the notch 57. This movement of the 70 plate 48 would lower the link 62 and also lower the link 66 so as to rotate the lever 68 clockwise and move the plate 70 out of a position where it might be engaged by the arm 71 so that the lever 72 would not raise the platen 1 into engagement 75

with the type wheels 53. This lowering of the link 62 would also rotate the arm 64 clockwise as viewed in Fig. 1, thereby rotating the lever 75 anti-clockwise as viewed in Fig. 2 and through 5 the roller and slot connection shown in Fig. 2 would rotate the levers 79 and 81 clockwise shifting the shifting plate 83 so as to disengage the lug 84 from the cut-away portion 85 of the plate 86 and so as to engage the radially extending lug 10 91 with the bifurcation 92 of the plate 86 and with the lugs 94 carried by the plate 83 secured to the main drive shaft 87. This elevation of the handle 20 has also raised the stud 106 out of the notch 107 of the plate 86 so that not only 15 is the said plate free to operate but is positively locked to the main drive shaft 87 so that as the main drive shaft operates the box cam 95 will operate the platen 100 and bring the certifying slip into engagement with the type wheels 102 as many times as there are lobes on the box cam. 20 Of course, there is shifting mechanism provided so as to shift the certifying card between the first, second, and third printed impressions which may be made thereon, but this mechanism forms no 25 part of the present invention and is not shown or described herein.

When the certifying card has been removed the rod 15 is moved downwardly by means of the spring 21 and the shutter 5 is moved downwardly 30 by means of the spring 19 which rotates the lever 28 counter-clockwise as viewed in Fig. 1 so that it engages the stud 36 and shifts the slide bar 31 into such a position that if the motor bar were now operated the roller 116 would engage the cam surface 117 as heretofore described.

I realize that many changes may be made in my invention without departing from the spirit thereof and I, therefore, desire to claim the same broadly except as I may limit myself in the appended claims.

Having now described my invention, I claim:

1. In a register, a certifying printing mechanism, a shutter normally preventing the insertion of a slip into the said printing mechanism, means whereby the shutter may be shifted so as to permit the insertion of a slip into the printing mechanism, a slide controlled by said means, a shiftable plate controlled by said slide, and means controlled by said plate to render said printing mechanism operative or inoperative.

2. In a register, a certifying printing mechanism, a shutter normally preventing the insertion of a certifying slip or card into said printing mechanism, a handle whereby said shutter may be operated, a shaft, means controlled by said shaft to render said printing mechanism operative or inoperative, and means whereby the said shaft is operated by the said shutter, said last-named means including a yieldable connection.

3. In a register having mechanism for printing on an inserted slip, and means for operating said printing mechanism, mechanism to control the operation of said printing mechanism by said operating means, a manually operable device 60 movable with relation to said printing mechanism into and out of a position to prevent the insertion of a slip to said printing mechanism, and an operative connection between said controlling mechanism and said manually operable device.

4. In a register having mechanism for printing on an inserted slip, and means for operating said printing mechanism, a manually operable device movable into and out of a position to prevent 70 the insertion of a slip to said printing mechanism,

and means controlled by said manually operable device to lock said printing mechanism against operation when said device is in a position to prevent the insertion of said slip.

5. In a register comprising receipt printing 5 mechanism, receipt issuing mechanism, mechanism for printing on an inserted slip, and an operable device for initiating the operation of said register, a device movable prior to the operation of said operable device into or out of a position 10 to prevent the insertion of said slip, and means controlled by the movement of the last mentioned device to control the operation of all of said mechanisms.

6. In a register comprising a receipt printing 15 mechanism, receipt issuing mechanism, separate mechanism for printing on an inserted slip, and an operable device for initiating the operation of said register, a device movable prior to the operation of said operable device into or out of a position 20 to prevent the insertion of said slip, and means controlled by the movement of said device to a position to permit the insertion of said slip to render said receipt printing and issuing mechanisms inoperative and to render said slip printing 25 mechanism operative.

7. In a register comprising an operating device, printing mechanism, and means for supporting a slip in a position to receive an impression from said printing mechanism, a manually operable device arranged normally to prevent the placing of a slip in said impression receiving position, normally inoperative means for operatively connecting said printing mechanism with said operating device, and means controlled by said manually 30 operable device to render said connection operative when said manually operated device is moved to a position to permit the placing of a slip in said impression receiving position.

8. In a register comprising an operating device, 40 printing mechanism, and means for supporting a slip in a position to receive an impression from said printing mechanism, a device movable into and out of a position to prevent the placing of a slip in said impression receiving position, means 45 for operatively connecting said printing mechanism with said operating device, and means controlled by the movements of said movable device to render said connecting means inoperative when said device is in a position to prevent the placing 50 of a slip in said position, and to render said connecting means operative when said device is in a position to permit the placing of a slip in said position.

9. In a register comprising an operating device, 55 printing mechanism, and means for supporting a slip in a position to receive an impression from said printing mechanism, a device movable into and out of a position to prevent the placing of a slip in said impression receiving position, means 60 for operatively connecting said printing mechanism with said operating device, and means controlled by the movements of said movable device to render said connecting means inoperative and to lock said printing mechanism against opera- 65 tion when said movable device is in a position to prevent the placing of a slip in said impression receiving position.

10. In a register having printing mechanism and a passageway through which a slip may be 70 inserted to receive an impression from said printing mechanism, an operable device to open and close said passageway, operating mechanism including a shaft, a cam adapted to be connected with or disconnected from said shaft, and means 75

controlled by said cam to actuate said printing mechanism, and means actuated by said operable device to control the connection between said cam and said shaft.

5 11. In a register comprising receipt printing mechanism, receipt issuing mechanism, an operating device and means for operatively connecting said operating device with both mechanisms, a device for initiating the operation of said register, a shutter operable independently of said operation initiating device, and means controlled by said shutter to control said connecting means.

10 12. In a register comprising receipt printing mechanism, certifying printing mechanism, an operating device and a device for initiating the operation of said register, means for selectively connecting said operating device with said printing mechanisms, a device operable independently of said operation initiating device to control the insertion of a slip to said certifying printing mechanism, and means controlled by the last mentioned device to control said connecting means.

15 13. In a register comprising receipt printing mechanism, certifying printing mechanism, and an operating device, separate means for connecting the respective printing mechanisms with said operating device, an operable device to control the insertion of a slip to said certifying printing mechanism, and means controlled by said operable device to render one of said connecting means operative and to render the other connecting means inoperative.

20 14. In a register comprising receipt printing mechanism and certifying printing mechanism, separately operable means for actuating the respective printing mechanisms, an operable device to control the insertion of a slip to said certifying printing mechanism, and means controlled by said operable device for rendering one actuating means operative and for rendering the other actuating means inoperative.

25 15. In a register comprising receipt printing mechanism and certifying printing mechanism, separately operable means for actuating the respective printing mechanisms, an operable device to control the insertion of a slip to said certifying printing mechanism, means controlled by said operable device for rendering one actuating means operative and for rendering the other actuating means inoperative, and means controlled by said operable device for locking that printing mechanism whose actuating means is inoperative.

30 16. In a register having receipt printing mechanism, and certifying printing mechanism and having a passageway through which a slip may be inserted to said certifying printing mechanism, a shutter to control the insertion of a slip through said passageway, separately operable means for actuating the respective printing mechanisms, and means controlled by the movement of said shutter to its open position to render the actuating means for said certifying printing mechanism operative and to render the actuating means for said receipt printing mechanism inoperative.

35 17. In a register having two separately operable printing mechanisms, a device separate from and movable with relation to both printing mechanisms to control the delivery of paper to one of said printing mechanisms, and means controlled by said operable device to render one printing

mechanism operative and to render the other printing mechanism inoperative.

40 18. In a register having two separately operable printing mechanisms, a device separate from both printing mechanisms and movable with relation thereto to a position to interrupt the delivery of paper to one of said printing mechanisms, and means controlled by the movement of said operable device to render inoperative that printing mechanism to which the delivery of paper has been interrupted.

45 19. In a register having two printing mechanisms, and an operating device, separate means for connecting said printing mechanisms with said operating device, an operable device for controlling the delivery of paper to one of said printing mechanisms, and means actuated by said operable device to control said connecting means.

50 20. In a register having two printing mechanisms and an operating device, separate means for connecting said printing mechanisms with said operating device, an operable device for controlling the delivery of paper to one of said printing mechanisms, and means controlled by said operable device to render one of said connecting means operative and the other connecting means inoperative when said operable device is in one position and to render the first mentioned connecting means inoperative and the last mentioned connecting means operative when said operable device is in another position.

55 21. In a register having two printing mechanisms, a slide, means controlled by the movement of said slide in one direction to render one printing mechanism operative and the other printing mechanism inoperative and controlled by the movement of said slide in the other direction to render the first mentioned printing mechanism inoperative and the last mentioned printing mechanism operative, an operable device to control the delivery of paper to one of said printing mechanisms, and means actuated by said operable device to control the movement of said slide.

60 22. In a register having a receipt printing mechanism, a receipt issuing mechanism, and a certifying printing mechanism, a slide, means controlled by the movement of said slide in one direction to render said receipt printing and issuing mechanisms operative and said certifying printing mechanism inoperative, and controlled by the movement of the slide in the other direction to render said certifying printing mechanism operative and said receipt printing and issuing mechanisms inoperative, an operable device to control the delivery of paper to said certifying printing mechanism, and means controlled by said operable device to actuate said slide.

65 23. In a register having receipt printing mechanism, certifying printing mechanism, and a passageway leading to said certifying printing mechanism, a shutter to open and close said passageway, a member yieldably connected with said shutter for movement thereby, and means controlled by the movement of said member in one direction to render said receipt printing mechanism operative and said certifying printing mechanism inoperative and controlled by the movement of said member in the other direction to render said certifying printing mechanism operative and said receipt printing mechanism inoperative.

70 WILLIAM G. ORTH.
